UNITED STATES PATENT OFFICE.

MICHAEL RICHEIMER, OF MASSILLON, OHIO.

ICE-CREAM FREEZER.

SPECIFICATION forming part of Letters Patent No. 252,254, dated January 10, 1882.

Application filed June 16, 1881. (No model.)

To all whom it may concern:

Be it known that I, MICHAEL RICHEIMER, a citizen of the United States of America, residing at Massillon, in the county of Stark and

5 State of Ohio, have invented certain new and useful Improvements in Ice-Cream Freezers; and I do hereby declare the following to be a full, clear, and exact description of the invention, such as will enable others skilled in the 10 art to which it appertains to make and use the same, reference being had to the accompanying drawings, and to letters or figures of reference marked thereon, which form a part of this specification.

15 This invention relates to improvements in ice-cream freezers of that class in which use is made of a reciprocating dasher or plunger, a rotating cream-vessel, a caged cover for said vessel, a crank for reciprocating the dasher or 20 plunger, and a gear mechanism for rotating the cream-vessel.

Figure 1 is a front view of the device. Fig. 2 is a vertical section.

In the drawings, A represents a bed-frame 25 for holding the stationary parts. To this bed-frame is secured an upright frame for the support of the power devices. This latter frame is composed of two uprights, B B, carried by expanded supports b b at the bottom.

30 C represents a shaft mounted horizontally in the uprights B B. It carries a large spur-wheel, D, between the uprights, a small pinion, E, at the inner end, and a crank, F, at the outer end.

35 Above and parallel to the shaft C another shaft, G, is mounted. It carries a spur-pinion, H, meshing with wheel D between the uprights B B, and carries a crank-wheel, I, at its inner end. This upper shaft, G, projects inward farther than the shaft C, for a purpose to be set 40 forth hereinafter.

J represents the ice-tub, within which is placed the cream-vessel K. The tub J is firmly held in place by means of strong uprights L L 45 and a raised portion, a, of the bed A. The cover of the cream-vessel is formed with a central tube or hollow boss, k, which provides a support for the upper end of the cream-vessel, and also permits the passage of the dasher- 50 rod.

M is a bar, which can be securely attached to the top of the uprights L L, and which has a central aperture for the mounting of the tube or boss k.

The cover is provided also with a crown spur-gear, l, which, when the parts are in working position, meshes with the pinion E. 55

m is the dasher, and M' the rod attached thereto for reciprocating it. The rod is pivoted to a pitman, N, which is in turn pivoted to 60 the crank-wheel I. The shaft G projects inward far enough to bring the pitman directly in the vertical plane of the dasher-rod. By means of a pin or pivot at n the pitman and rod M' are detachably connected together. 65

In operation the tub J, after the cream-vessel and the ice have been introduced, is pushed back until the pinion E is in gear with the crown-wheel l, the uprights L L serving to guide the tub and to brace it. The bar M is 70 then placed in position and fastened by pins o o passing through studs m' m', projecting upward from the uprights. The pitman N is then pivoted to the rod M', and the device is 75 ready for working. If the crank F be rotated, the cream-vessel will be revolved by the pinion E and wheel l and the dasher will be reciprocated by the crank-wheel I and the pitman N.

I am aware that heretofore use has been 80 made of gearing and cranks to produce simultaneously a rotation of the cream-vessel and a reciprocation of the dasher, such devices being shown in the patents to Lipp, No. 62,429, February 26, 1867, and Rote, No. 113,450, 85 April 4, 1871; and I do not claim, broadly, such devices as my invention; but the devices that have been heretofore used for these purposes have not been combined with the ice-tub and the cream-vessel in the manner which 90 I employ, nor has the gearing used been of the nature of mine. I so arrange the ice-tub relatively to the gearing-frame and combine with it uprights of such nature that it can be held firmly in position both at the top and bottom independently of said gearing-frame, and yet at the same time allow of its being independently detached from said gearing-frame without moving the latter. 95

What I claim is—

The combination of the uprights L L, the cross-bar M, supported independently of the ice-tub and of the gearing-frame, the mechanism for rotating the freezer and reciprocating the dasher, the ice-tub J, and the frame B b, which supports the gearing entirely independently of the ice-tub, substantially as set forth.

In testimony whereof I affix my signature in presence of two witnesses.

MICHAEL RICHEIMER.
